UNITED STATES PATENT OFFICE.

GORDON W. BRADY, OF NEW YORK, N. Y., ASSIGNOR OF ONE-HALF TO
GEORGE M. RITTENHOUSE, OF SAME PLACE.

STREET-SWEEPER.

SPECIFICATION forming part of Letters Patent No. 634,283, dated October 3, 1899.

Application filed January 9, 1899. Serial No. 701,656. (No model.)

To all whom it may concern:

Be it known that I, GORDON W. BRADY, a citizen of the United States, residing in the city of New York, Brooklyn borough, in the county of Kings, and State of New York, have invented new and useful Improvements in Street-Sweeping Machines, of which the following is a specification.

This invention relates to street-sweeping machines of the type having a hollow bucketed wheel to take up sweepings from a road or other surface and deposit same continuously in a receptacle, the main features of the invention residing in the means of more effectively performing such operation and in the construction and arrangement of parts in the apparatus, as will be specifically referred to hereinafter and particularly pointed out in the claims.

20 In the drawings forming part of this specification, Figure 1 is a top plan view, partly in horizontal section, of my entire apparatus. Fig. 2 is a side elevation of the bucketed wheel looking toward the interior thereof. 25 Fig. 3 is a vertical section taken on the line 3-3 of Fig. 2. Fig. 4 is a detail of the bracket holding the spring-supports for the guide-strip. Fig. 5 is another detail view more clearly showing the means of connection between the bracket and spring-supports. 30 Fig. 6 is a detail of the buckets in the wheel looking from line 6-6 of Fig. 7 in the direction of the arrow. Fig. 7 is a detail cross-section of a bucket. Fig. 8 is an enlarged detail of 35 the clutch for operating the broom, and Fig. 9 is a detail of a section of buckets as formed.

In said drawings, A indicates the frame which supports the mechanism and parts comprising my apparatus and which is mounted 40 upon wheels B C D D, the wheel C having a hollow casing secured at its inner surface and arranged to rotate therewith. The said casing comprises a circular plate E, of substantially the same diameter as wheel C, and a series of buckets e, extending at right angles from plate E, continuing in annular form around its perimeter and opening centrally. The said buckets are bolted together and to the wheel-felly through the plate E by bolts 45 e', as seen, thereby rendering the buckets e,

the plate E, and the wheel C integral. The buckets e are preferably made separately and initially united together in curved lengths, as seen in Fig. 9, being thus ready to be adapted to the wheel, this being for convenience of manufacture. The particular shape or individual arrangement of said buckets is most clearly shown in Figs. 6, 7, and 9, and the purpose of the central inclination of their peripheral walls is to permit the sweepings when deposited within the buckets at the base-line of the wheel to drive with the aid of gravitation into the rearmost portion of said buckets and to be retained therein while the buckets are being raised with the rotation of the wheel. The abutting walls of the buckets are inclined in the direction of rotation, Fig. 6, to more securely retain the contents while being raised and to facilitate the discharge of such contents as each bucket reaches approximately its highest point of travel.

F indicates the axle of wheel C, its free end being journaled at f in a bearing attached to frame A, the said axle or shaft carrying a sprocket-wheel G, which is rigid therewith.

H indicates a circular broom or sweeper which is mounted on shaft h, which latter is journaled at h' h² in hangers h³ h⁴, said hangers being respectively loosely supported by brackets h⁵ h⁶, which are thus secured to the frame A, as seen. The sweeper, as seen, is arranged transversely diagonally of the apparatus, the inclination in the forward movement of the apparatus being toward the bucketed wheel C.

Centrally upon the broom-shaft h is rigidly mounted a sprocket-wheel I, with which a sprocket-chain i intermeshes to rotate same and the broom, said sprocket-chain also meshing with the teeth of a sprocket-wheel J, which latter is rigidly mounted upon a shaft j. The shaft j is journaled in bearings j' j² and terminates at its inner end in a universal joint j³, with which is connected a shaft j⁴, supported in bearing j⁵, and having a pinion j⁶ secured at its end.

K indicates a shaft which is loosely mounted in a bearing k secured to the frame A and supports rigidly a gear-wheel k², which is 100

adapted, as seen, to mesh with the pinion j^6 . The shaft K also bears a slidable sleeve k' thereon, which is prevented from independent rotation by a key fitting in a longitudinal slot 5 k and being free to slide therein. The sleeve k' bears at one end a collar l , and at its other end it bears a clutch portion k^3 , having teeth adapted to engage with the teeth of a corresponding clutch portion k^4 , which latter is 10 fast upon the shaft K. A sprocket-wheel k^6 , mounted upon a hub k^5 , is also mounted upon the shaft K. A sprocket-chain L connects the sprocket-wheels G and k^6 and permits the latter to be rotated by the former. The movement of sprocket G being forward with the travel of wheel C, a like movement is communicated to sprocket k^6 , whence when the clutch portion k^3 is engaged with the clutch portion k^4 such movement is communicated 15 through sprocket k^2 to pinion j^6 , but giving the latter the reverse movement, which reverse movement is communicated through shaft j , sprockets J I, and shaft h to the brush or sweeper II, as is requisite to cause the 20 sweepings to be directed forwardly.

M indicates a yoke which straddles the sleeve k' between collar l and the clutch portion k^3 to move said clutch-piece into or out of engagement with the clutch portion k^4 . 30 Said yoke M is operated through the medium of a rod m' , which is slidably held in a strap-bearing m^2 , said rod being bent at m^3 beyond the bearing and terminating in a pivotal connection m^4 with a bell-crank lever m^5 , which lever is provided with a weight m^6 at its free end. The lever m^5 is allowed vertical movement within a slotted bearing m^7 and can be operated by hand to cause the clutch portion k^3 to be moved into or out of engagement with 40 clutch portion k^4 through the mechanism described. The lever m^5 is pivoted in a bearing m^6 , as seen, and is locked in its desired position within bearing m^7 by a pin m^8 .

Secured to the hangers h^2h^4 are angle-brackets i^1i^2 , which in turn support a substantially T-shaped dashboard composed of the vertical member N and horizontal member N', that extends the entire length of the broom II, parallel therewith and slightly in advance thereof. The function of this board N N' is to check and restrain the throw of the sweepings, which otherwise by the operative movement of the brush would be scattered ahead. Slots n are formed in the board N' and bolts 55 n' are passed through said slots into the board N, firmly uniting both of said boards. By means of this slot a bolt fastening the horizontal board N' may be adjusted to any required degree with regard to the broom II. 60 The board N' is raised sufficiently above the road-surface to avoid striking against stones and other projections; but at the point where said board extends into the bucketed wheel C it is provided with a depending extension-piece N², of leather, rubber, or other flexible material, whose lower edge trails the road-surface and also sets snugly upon the flange-

plates O, thereby positively preventing the throw of sweepings elsewhere than into the bucketed wheel C.

Returning to the description of the bucketed wheel C, into which one end of brush II extends diagonally to insure the deposit of the sweepings therein, I provide a flexible flange therefor composed, preferably, of thin metallic plates O, the said plates lapping one another and forming a circular inclined flange, its inner diameter being less than its outer diameter. At its diminished diameter said flange meets the inner circular flange of the 80 buckets e and it flares outwardly therefrom, as seen, to come in contact with the road being traversed, at which point of contact said flange flattens to form an efficient scoop and to assist the passage of sweepings thereover, 85 the sweepings passing through into the buckets e. P is an annular strip of metal encircling and extending beyond the bucketed wheel C and lapping the connecting portions of flange-plates O. An annular strip Q of 90 wood or other suitable material of substantially triangular cross-section is filled in the space between the bucket ends, the strip P, and flange-plates O. The strip P is bolted to buckets e, and the flange-plates O are secured 95 upon the strip Q. I have found in practice that plates of thin sheet-steel, as the plates O, serve to form a very flexible, efficient, and durable sweepings-receiving flange for a bucketed wheel.

Sweepings deposited in the bucketed wheel C are carried upwardly therein by its rotation and are intended to fall from the upper portion of said wheel by gravitation downwardly through chute R into the cart S. To 100 prevent the sweepings from falling out of the buckets prior to their reaching the point below which the chute is stationed, I provide a stationary guard T, which is held in its fixed position, as indicated, in the following manner: The said guard T consists, preferably, of a sheet of metal curved to fit closely against the mouths of the passing buckets e, and said guard is supported and held tensionally in its position by a pair of spring-arms U, the latter being adjustably connected to a bracket V, which is itself bolted to the frame A, the bolts 105 v passing through the slot v' . I preferably clamp the spring-arms U to the bracket V as follows: I employ a T-shaped clamping-piece 110 having opposite arms u^1u^2 and a bifurcated stem portion u^3 , which straddles the bracket V, being secured thereto by screw u^4 . The spring-arms U pass between and are held by the arms u^1u^2 and the bracket, and their ends 115 are limited by the stems of headed bolts u^5 , against which they abut, the said bolts u^5 being placed in portions u^6 , extending from bracket V. Rubber or other packing material v^2 is placed between the spring-arms U 120 and their seat upon the bracket V to enable the clamping to be more effective. The guard-strip T, thus spring-held against the buckets e in their upward travel, prevents the falling

out of the sweepings until they arrive at a point directly over chute R, at which point the guard-strip T terminates, having performed its function.

5 W is a strip of wood secured at the edge of strip T and having its lower end w curved away from the buckets e, as seen, its purpose being, in the case of sticks and like articles being carried upward with the sweepings, to 10 enable such sticks, &c., to enter between such strip W and to pass upwardly between the guard T and the buckets e, being forced by the movement of the latter, and, in their travel, pressing the guard-strip against its spring 15 tension, sufficiently apart to permit of their passage.

The purpose of flexibly supporting the guard-strip T will now be clearly comprehended, since were it rigidly secured in position it and the buckets e would be liable to damage when sticks and other like obstructions were attempted to be carried upwardly by the buckets.

The chute R is supported upon a bracket 25 r, which is mounted upon frame A, as seen, said chute being at a suitable inclination, and its base portion extends upwardly to form a curved rear wall r', which meets the edge of the rear wall of the passing buckets e, so as 30 to form a continuous line therewith and prevent escape of the falling sweepings excepting through the chute. The lower end of the chute R terminates at a point aside from or out of the path of the cart S in tipping; but 35 an extension R' is hinged to the chute proper, as seen, and said extension projects directly over the cart. When the latter is tipped to dump the contents, its wall strikes against the chute extension R' and raises it upon its 40 hinges, and upon the reseating of the cart the extension again drops into operative position by gravity. Said extension R' is preferably made of flexible material. The chute is provided with a bail or arch R², as seen, whereby 45 a bag or sack may be fitted over the mouth of said chute in case it is desired to deposit the sweepings into such a receptacle instead of into the cart.

The cart may be tipped by any suitable 50 means, and I have shown in the drawings a compound lever device X for this purpose, the same being operated from the driver's seat by a handle Y.

W indicates a lever intended to raise the 55 broom H out of contact with the road, said lever being fulcrumed at w and engaging at one end with a chain w', which is connected to a bar w², the latter being a continuation of the angle-brackets i i'. The lever W terminates in a handle w³ near the driver's seat, said lever also being provided with a sliding weight w⁴ to regulate its power and being allowed vertical play within a strap-bearing w⁵, within which it may be secured in any desired 65 position by a pin w⁶.

Y' indicates an auxiliary chute arranged at the forward side of chute R and intended

to receive such contents of the buckets e as may not be discharged through chute R, the chute Y' serving to convey such undischarged 70 sweepings into the buckets descending forwardly. The lower end of chute Y is connected to the frame in any suitable manner.

Having now described my invention, I declare that what I claim is—

75 1. In a street-sweeping machine, a hollow wheel open at one side to receive sweepings and a flaring flange therefor attached to the open side, said flange consisting of a series of thin metal plates connected in annular form. 80

2. In a street-sweeping machine having a hollow wheel open at one side to receive sweepings, an outwardly-extending flaring flange therefor to flatten as a scoop by contact with the road, said flange comprising a 85 series of sheet-metal plates connected together and arranged in circular, inclined form, and connected to said wheel to direct sweepings therein.

90 3. In a street-sweeping machine having a hollow bucketed wheel to receive and raise sweepings to an uppermost point of discharge, a stationary guard-plate covering said buckets while being raised, and a flexible support mounted upon the frame of the machine and 95 arranged to hold said guard-plate yieldingly against the moving buckets.

4. In a street-sweeping machine, a frame, a hollow bucketed wheel rotatably connected therewith, a bracket connected to said frame, 100 a pair of spring-arms adjustably clamped to said bracket, and a curved guard-plate supported by said spring-arms in position to cover the ascending buckets.

5. In a street-sweeping machine, a frame, 105 an axle rotatably supported therein, and a hollow bucketed wheel mounted upon said axle and arranged to receive and raise sweepings; together with a brush to drive the sweepings into said hollow wheel, said brush being 110 rotatably supported in hangers attached to the frame; a sprocket-wheel upon said axle, another sprocket-wheel mounted upon a shaft journaled in the frame in advance of the first-named sprocket-wheel, a chain connecting 115 said sprockets, said shaft bearing a straight gear-wheel, which it rotates; a pinion mounted upon a rotating rod and meshing with said gear-wheel, another rod connected with said rotating rod by a swivel-joint and extending 120 transversely across the frame in parallelism with the brush, and bearing a sprocket-wheel from which extends a sprocket-chain connecting it with a sprocket-wheel upon the shaft to rotate said brush. 125

6. In a street-sweeping machine, a frame, a hollow bucketed wheel C, an axle F therefor, a sprocket G upon said axle, a shaft K, a sprocket k⁶ thereon, a chain connecting sprockets G and k⁶, a clutch portion k⁴, a 130 sliding sleeve k', bearing collar l and clutch portion k³; a gear k² upon shaft K, a pinion j⁶ meshing therewith and supported upon shaft j⁴, a rotating rod j connecting with shaft

*j*⁴ by a universal joint, a sprocket *J* upon *j*, a circular brush *H* mounted diagonally in frame *A* upon shaft *u* by hangers *h*³ *h*⁴, a sprocket *I* upon said shaft *h*, and a chain *i* connecting 5 sprockets *J* and *I*, together with a yoke *M* straddling sleeve *k*', a rod *m*' supporting said yoke, and a bell-crank lever *m*⁵ to operate said rod and yoke to engage or disengage the clutches.

10 7. In combination with a suitable frame, a brush mechanism, a T-shaped dashboard consisting of a vertical strip and a horizontal strip adjustably secured thereon, said dashboard being supported clear of the road in 15 advance of the brush; together with a bucketed wheel, to receive sweepings, said wheel having a flaring flexible flange, and a piece of flexible material depending from the dashboard, having its lower edge trailing the 20 road and lying snugly against the aforesaid flange.

8. In a street-sweeping machine, a hollow wheel open at one side to receive sweepings and comprising a circular plate and a series 25 of buckets arranged and secured side by side

and opening centrally of the wheel, the bases of said buckets forming the wheel-perimeter being transversely inclined to provide their deepest and most capacious portion at the outer wall.

9. In a street-sweeping machine, in combination, a hollow wheel, open at one side to receive sweepings and comprising a circular plate and a series of buckets arranged side by side and secured together, to receive, elevate, and discharge sweepings, the said buckets opening centrally of the wheel and having their meeting walls arranged at inclines transversely of the wheel-perimeter, to form a lowermost pocket against the outer wall of 40 the buckets at the upwardly-turning portion of the wheel.

In testimony whereof I have hereunto set my hand in the presence of two subscribing witnesses.

GORDON W. BRADY.
